CLAIM

We claim the ornamental design for a keyboard for portable computer, as shown and described.

DESCRIPTION

FIG. 1 is a front perspective view of a keyboard for portable computer of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a front perspective view of the keyboard for portable computer of FIG. 1, shown in a first state of use with an additional environmental portable computer; and, FIG. 10 is a front perspective view of the keyboard for portable computer of FIG. 1, shown in a second state of use with an additional environmental portable computer.

Broken lines showing the portable computer in FIGS. 9 and 10 depict unclaimed environment and form no part of the claim. All other broken lines in the drawings depict portions of the keyboard for portable computer that form no part of

(Continued)

the claimed design. Unshaded areas between broken and solid lines of FIG. 7 form no part of the claimed design.

1 Claim, 10 Drawing Sheets
